CLAIM

The ornamental design for a hand lamp, as shown and described.

DESCRIPTION

FIG. 1 is an upper perspective view of a hand lamp showing my new design;

FIG. 2 is a front view thereof;

FIG. 3 is a rear view thereof;

FIG. 4 is a side view thereof;

FIG. 5 is an opposite side view thereof;

FIG. 6 is a bottom plan view thereof;

FIG. 7 is a top plan view thereof; and,

FIG. 8 is a lower perspective view of thereof.

The broken lines depict unclaimed portions of the hand lamp that form no part of the claimed design.
